Ray E. Hall
By: Wm A. Belf
Hilley.

UNITED STATES PATENT OFFICE.

RAY E. HALL, OF CHICAGO, ILLINOIS, ASSIGNOR TO HALL RESEARCH CORPORATION, OF CHICAGO, ILLINOIS, A CORPORATION OF DELAWARE.

TONE-SELECTIVE RECEIVER.

Application filed June 17, 1922. Serial No. 568,939.

This invention relates to apparatus for receiving communications and has for its primary object to permit selected signals only to be received while all others are excluded.

A further object of the invention is to provide for a wide range of selection in signals and the accurate exclusion of all except the particular signal selected.

10 A further object of the invention is to permit the selection of any particular tone from a number that may be present so that communication may be carried on with that tone without interference from or with other 15 tones.

Further objects of the invention will become apparent as the description is read in connection with the accompanying drawings, in which

20 Fig. 1 is a diagrammatic view showing one embodiment of the invention; and

Fig. 2 is a modified form of the invention.

This invention is based upon the well known laws governing the vibration of 25 strings, and in Fig. 1 I have shown a very satisfactory arrangement for receiving small alternating or pulsating currents and delivering corresponding vibrations for selected tones to a stethoscope. In this illustration, 30 10 indicates a string which may be of any suitable form or material that will operate according to the laws mentioned. One end of the string is fixed to a heavy mass or other stationary support 11 and the opposite end is adjustably connected to a similar support 12. I have shown this support 12 with a 35 polygonal opening 13 receiving a similarly shaped plug 14 having a threaded socket 15 to receive a screw 16 having a head 17 working against the washer 18. The free end of the plug 13 is connected with a strong spring 19 which in turn is connected with the string 10. The adjustable connection is used to tune the receiver by adjusting the tension of 40 the strings and the spring is desirable to permit vibrations lengthwise to the string while maintaining the tension thereon.

In this device the signals are received by 45 a telephone magnet 20 which operates a reed 21 having one end attached to the string 10 at 22 and the other end suitably fixed to a support at 23. The currents set up by the incoming signals will cause the magnet to operate the reed in much the same manner 50 that the ordinary telephone diaphragm is

operated and the vibrations will have a tone corresponding to the tone of the signal. I have used the term "reed" to describe an instrument that will vibrate after the manner of the reed in musical instruments, but I do not intend to be limited in this or any respect, except as made necessary by the prior art. The invention may be applied to anything that will make vibrations corresponding to alternating or pulsating currents.

The string 10 is biased to one side by a rod 24 connected to the middle of the string at one end and at the other end with a spring 25 which in turn is connected with an adjustable plug 26 carried by a suitable support 27. The plug 26 is mounted similar to the plug 13 so that the bias of the string may be adjusted to suit particular conditions. The spring 25 is relatively light so as to 75 permit the string 10 to vibrate transversely with comparative freedom, but prevents it from becoming straight and thus not vibrating freely. A rod 28 is connected to the string at the same point as the rod 24 and 80 carries a float 29 resting on the small diaphragm 30 in a stethoscope 31 having an ear piece 32 at the end opposite the diaphragm. The rod 28 may be connected to the diaphragm in any other suitable manner so as to communicate the transverse vibrations of the string thereto. The stethoscope is used in this illustration merely as an example and it will be clear that any other suitable receiver may be used in its place.

When a signal is received by the magnet 20, the reed will be vibrated and by varying the tension on the spring will have a tendency to alternately lower the point 33 in the spring and permit it to be raised. When the period of the signal corresponds to the period of the string, the cumulative action of the reed will cause the comparatively wide transverse vibrations of the string.

Inasmuch as the frequency of the string varies according to the tension, length and mass, a very wide range of periods can be given to the string by changing these factors. Consequently, a device of this kind can be 100 made adjustable to suit a very great range of tones used in signaling.

The string can be tuned by adjusting either or both of the plugs 13 and 26 to give any tone within the range of its length 110

and mass. Different lengths and different masses can be used to give the instruments different ranges and by a suitable selection the instruments can be made to equip a line 5 of communication so that a great variety of signaling tones can be used simultaneously while each instrument can be tuned to receive only selected tones within its particular range. These possibilities of the invention make it particularly adaptable to 10 use in multiplex telegraphy and in radio reception in which there is ordinarily interference, and those skilled in the art will readily find other uses for it.

15 In Fig. 2, I have shown a modified form in which a string 35 is stretched between fixed supports 36 and 37 and made adjustable by a plug 38 similar to that shown at 13. However, in this form I have made 20 provision for using two segments 39 and 40 of the string operated by a single reed 41, the segments being biased in opposite directions by adjustable plugs 42 and 43 operating through springs 44 and 45 and rods 46 25 and 47 corresponding to the similar parts in Fig. 1. The right end of the segment 39 is determined by a point of connection with a rocker 48 having relatively great mass, which rocker is preferably located on 30 the opposite side of the spring 49 from the plug 38. This sort of an apparatus is more highly selective than that shown in Fig. 1 and is given merely to indicate how those skilled in the art will readily modify the 35 physical form to suit conditions to be met in practice.

In both these forms I have shown the string biased by a rod connected with the string, but it will be understood that in 40 some instruments gravity will give the wire sufficient bias to produce the necessary results and in other instruments various other suitable means may be resorted to.

I am aware that changes may be made in 45 the form, construction and arrangement of the invention, as set forth in the selected embodiment herein, without departing from the scope or sacrificing any of its material advantages, and I therefore reserve the right 50 to make all such changes as fairly fall within the scope of the following claims.

I claim:

1. A tone selective receiver comprising a 55 string, said string being stretched between two supports and fixedly held at one end, means for adjusting the tension on said string, means for causing transverse vibrations of said string, and signal receiving means connected to said string and operated by said vibrations.

2. A tone selective receiver comprising a 60 string, said string being stretched between two supports and fixedly held at one end, means for adjusting the tension on said 65 string, means for transforming variations in

an electric current into transverse vibrations of said string, and signal receiving means connected to said string and operated by said vibrations.

3. A tone selective receiver comprising a 70 string, said string being stretched between two supports and fixedly held at one end, means for adjusting the tension on said string, means for causing transverse vibrations of said string, signal receiving means 75 connected to said string and operated by said vibrations, and means to bias said string at the point of its connection to said receiving means.

4. A tone selective receiver comprising a 80 string, said string being stretched between two supports and fixedly held at one end, means for adjusting the tension on said string, means for transforming variations 85 in an electric current into transverse vibrations of said string, signal receiving means connected to said string and operated by said vibrations, and means to bias said string at the point of its connection to said receiving 90 means.

5. A tone selective receiver comprising a 95 string, said string being stretched between two supports and fixedly held at one end, means for adjusting the tension on said string, means for causing variations in the tension of said string, said variations resulting in transverse vibrations thereof, and signal receiving means operated by said vibrations.

6. A tone selective receiver comprising a 100 string, said string being stretched between two supports and fixedly held at one end, means for adjusting the tension on said string, means for causing variations in the tension of said string by variations in an 105 electric current, said variations in tension causing transverse vibrations, and signal receiving means operated by said vibrations.

7. A tone selective receiver comprising a 110 string, said string being stretched between two supports and fixedly held at one end, means for adjusting the tension on said string, means for causing variations in the tension of said string, said variations resulting in transverse vibrations thereof, signal 115 receiving means operated by said vibrations, and means to bias said string at the point of its connection with said receiving means.

8. A tone selective receiver comprising a 120 string, said string being stretched between two supports, means for adjusting the tension on said string, means for causing variations in the tension of said string by variations in an 125 electric current, said variations in tension causing transverse vibrations, signal receiving means operated by said vibrations, and means to bias said string at the point of its connection with said receiving means.

9. A tone selective receiver comprising a 130 string, said string being stretched between

- two supports, means for adjusting the tension on said string, means for causing variations in the tension of said string, said variations resulting in transverse vibrations thereof, signal receiving means operated by said vibrations, means to bias said string at the point of its connection with said receiving means, and means to adjust said last named means.
10. 10. A tone selective receiver comprising a string, said string being stretched between two supports, means for adjusting the tension on said string, means for causing variations in the tension of said string by varia- tions in an electric current, said variations in tension causing transverse vibrations, signal receiving means operated by said vibrations, means to bias said string at the point of its connection with said receiving means, and means to adjust said last named means. 15
11. The combination of a string, means for putting the string under tension, yielding means to bias the string between its ends, a reed connected with the string, a magnet for vibrating the reed and a stethoscope connected with the string at the bias. 20 25

RAY E. HALL.
